UNITED STATES PATENT OFFICE.

JARED E. BELT, OF MINNEAPOLIS, MINNESOTA.

CURRENT-MOTOR.

No. 895,534.

Specification of Letters Patent. Patented Aug. 11, 1908.

Application filed July 27, 1903. Serial No. 167,175.

To all whom it may concern:

Be it known that I, JARED E. BELT, of Minneapolis, in the county of Hennepin, State of Minnesota, have invented certain new and useful Improvements in Current-Motors, of which the following is a specification.

This invention relates to improvements in motors adapted to be actuated by a current 10 of water, either from a running stream or from the ebb and flow of the tide, and the invention consists generally in the constructions and combinations, hereinafter described and particularly pointed out in the claims.

15 In the accompanying drawings, forming part of this specification, Figure 1 is a plan view of a motor embodying my invention. Fig. 2 is a side elevation of the same. Fig. 3 is a transverse section on line $x-x$ of Fig.

20 1. Fig. 4 is a detail plan of the means for supporting and adjusting the device. Fig. 5 is a detail section on line $y-y$ of Fig. 4. Fig. 6 is a detail of the flexible blade. Fig. 7 is a detail showing a modified construction 25 of the blade.

In the drawings, 2-2 represent suitable channel beams that are secured to the walls 30 of a flume or channel, or floats that may be used to support the motor, through which the water, that is to operate the motor, passes. These channel beams are of any suitable size and they are supported in any suitable manner.

3 represents an upper horizontal beam 35 and 5 a lower horizontal beam or base plate or sill. The beam 3 and base plate 5 are connected by the vertical channel beams 7, preferably bolted securely at the top and bottom to said beam and base plate. A 40 series of frames 9 (as here shown, three in number) are secured to the channel beams 7 at each end of the device and these frames are provided with the rolls 11 that bear upon opposite flanges of the beams 2 (see Fig. 4).

45 These frames embrace the channel beams 2 and hold the device in position so that it can be raised and lowered upon said channel beams. As there would be considerable friction between the movable frames and the 50 channel beams 2, owing to the pressure of the water upon the motor, I prefer to provide the wheels or rolls 11 that are adapted to roll upon the edges of the channel beams 2-2. These rolls are preferably provided 55 upon each edge of the channel beams so as to maintain the motor frame in proper position

and permit of its being vertically adjusted with ease.

Upon the inside of the channel beam 2 is a bracket 13 having a socket that forms and 60 has a bearing for a suitable ball 15. A nut 17 is bolted upon the edge of the channel beam 7 and a screw rod 19 having a hand wheel 21, passes through a lug 23 secured upon the channel beam 2 and engages the 65 threaded nut 17 and the lower end of said rod rests upon the ball 15. The nut 17 and screw 19 support the entire weight of the device and this weight is transmitted, through the ball 15 and bracket 13, to the 70 channel beam 2. By means of this screw connection the apparatus may be raised or lowered and any desired portion of the blades, hereinafter described, may thus be submerged in the water. I also provide at 75 the top and bottom of the apparatus the horizontal parallel channel beams 25 and 27. These are connected to the horizontal beam 3 and the base plate 5 by suitable brace rods 29 and 31.

80 Mounted in bearings upon the horizontal beam 3 and the base plate 5, are the shafts 33, one at each end of the device, and these shafts preferably have their lower ends mounted in step bearings 35 upon the base 85 plate 5, said step bearings being each preferably provided with an anti-friction roller 15 (see Fig. 3). The shafts 33 are provided with the sprocket wheels or pulleys 37 and the upper ends of the shafts 33 are preferably 90 provided with beveled pinions 39 engaging corresponding pinions 41 upon a horizontal shaft 43. This shaft is provided with a suitable belt pulley 45 to which a belt may be applied for driving any suitable machinery 95 that it is desired to operate from this motor, or metal shive for use of wire rope device. Suitable endless chains 47 and 49 are arranged upon the wheels 37 and these chains are connected to a series of posts 51 provided 100 at their upper and lower ends with anti-friction rollers 52 adapted to travel in the channels of the beams 25 and 27. To each of the posts 51 is hinged a blade or plate 53 and suitable check chains 55 connected to the 105 free edges of the blades are each connected also to the next succeeding post 51.

110 This device is arranged either across a running stream or in such position that it will stand substantially at right angles to the direction of the flow of the tide. When the water is passing through the motor in the

direction of the arrow at the bottom of Fig. 1, the blades 53 will assume the position shown in Fig. 1 of the drawings. As soon as the blades are carried around the sprocket 5 wheels with the chains engaging said wheels, the blades swing upon the posts into the opposite position.

The operation of the motor will be readily understood from the foregoing detailed description. The parts being in the position shown in Fig. 1 of the drawings and the motor being properly submerged, a current of water flowing in the direction of the arrow in the lower part of said figure, will strike 10 against the blades 53 and these blades being in an inclined position, the force of the water will cause the blades to travel to the right. As the water passes through the motor it strikes the blades at the opposite side and 15 causes them to travel toward the left. This operation being continuous, the shafts 33 and the driving shaft 43 will be continuously 20 rotated. The motor is capable of operation in either direction. Should the direction 25 of the flow of the water change and the water pass in the opposite direction through the motor, the position of the blades 53 will be reversed without changing the direction of movement of said blades and the supporting 30 chains or the driving shaft.

For the purpose of increasing the power of the motor, I prefer to make the blades 53 flexible so as to permit them to bend under the pressure of the water, as shown in the detailed drawings, Figs. 6 and 7. These blades 35 are preferably made of sheet steel or other suitable material that will bend readily under the pressure of the water and that will resume their normal form in passing around the sprocket wheels at the end of the machine 40 and will then bend in the opposite direction when subjected to the pressure of the water at the other side of the motor. Instead of forming the blades of sheet steel, I may form 45 such blades of two or more strips, suitably hinged together, and capable of flexing in either direction, as illustrated in Fig. 7.

The upper and lower channel beams 25 and 27 receive the rolls on the upper and 50 lower ends of the posts 51 and form guides therefor and thereby retain said blades in the proper position while they are being subjected to the pressure of the water.

Where the flexible blades are used, the 55 pressure of the water causes these blades to bend as indicated in Figs. 6 and 7 of the drawings. The moving water remains in contact with the blades and exerts pressure thereon for a longer period of time than it 60 would do if flat, rigid blades were employed.

In some instances it is preferable to provide a hood attachment which is secured to the frame work of the motor and comes down near to the surface of the water when the 65 motor is submerged, covering the machinery

to retain the heat produced by the motor or heat that may be supplied to the interior of the hood for the purpose of preventing the formation of ice over and around the motor. I have shown in the drawings a construction 70 suitable for this purpose. As here shown, secured to the upper bars 25 are the bows 57 and 59. The bows 57 extend around the end of the motor and the bows 59 over the top. A canvas or other suitable hood 61 is 75 secured upon these bows and covers the upper part of the motor. When the motor is submerged, the edge of the hood comes down near to the surface of the water and protects the motor and prevents the formation of ice 80 thereon.

If desired, a suitable steam or hot air pipe may be arranged to project into the space within the hood so as to heat the air within this space. A suitable opening is provided 85 in the hood for the passage of the driving belt.

A suitable scale 63 is preferably provided upon the stationary channel beams 2 so as to show the depth to which the blades of the 90 motor are submerged. The power of the motor is governed by the amount that the blades are submerged.

The line shaft is, with this construction, driven from either end with equal force by 95 the same power, thus doing away with springing or twisting of the shaft, by which means a shaft of smaller diameter may be used.

In light power plants where narrow blades 100 only are required, uniform thickness of blade to form proper curve, may be used; but when power required is great enough and volume and velocity of water will warrant it, the blades may be made the proper thickness 105 at the center, tapering by gradation in its thickness to either edge on the principle that a buggy spring is strengthened, leaf by leaf, to support it, thus to support a uniform curve when in action preventing, by this means, in heavy work the blade from forming 110 into a kink or angle at any point in its surface.

By having the blades curved, I find that they offer less resistance to movement through 115 the water, thus requiring less power to operate the motor.

I may arrange suitable wings at each side of the current motor to act as wing dams and direct the water through the motor. 120

I claim as my invention:

1. The combination, in a current motor, with the vertically adjustable frame, of the movable blades supported thereby, supporting bows arranged upon said frame, and a hood 125 secured upon said bows and inclosing the upper part of the motor, substantially as described.

2. The combination, with the vertical stationary channel beams 2, of the vertically 130

adjustable frame, adjusting means for said frame arranged upon said channel beams, vertical shafts secured upon said frame, two pairs of carrying wheels on said shaft, the endless belts or chains arranged upon said 5 wheels, posts or bars connecting said chains, flexible blades or plates hinged upon said posts, and stay chains connected to said

posts and to the free edges of said blades, substantially as described. ¹⁰

In witness whereof, I have hereunto set my hand this 22d day of July, 1903.

JARED E. BELT.

In presence of:

A. C. PAUL,
C. G. HANSON.
